UNITED STATES PATENT OFFICE.

CHARLES A. HUSSEY, OF NEW YORK, N. Y., ASSIGNOR OF ONE-HALF TO
JOSEPH SNYDER, OF PHILADELPHIA, PENNSYLVANIA.

ELECTRIC LIGHTING ATTACHMENT FOR GAS-FIXTURES.

SPECIFICATION forming part of Letters Patent No. 320,065, dated June 16, 1885.

Application filed January 13, 1885. (No model.)

To all whom it may concern:

Be it known that I, CHARLES A. HUSSEY, of New York, in the county of New York and State of New York, have invented a certain new and useful Improvement in Electric Lighting Attachments for Gas-Fixtures, of which the following is a specification.

The object of my improvement is to provide a simple and unobtrusive attachment to a gas-fixture, whereby an electric battery and a coil for electric lighting appliances may be supported.

My improvement consists in a clamp or attachment made in two sections connected, so as to admit of their separation to enable them to be slipped onto the stem of a gas-fixture transversely to the length of the latter, and so as to admit of their being clamped upon the same, said clamp having ring-shaped portions, and being combined with cases fitted in the ring-shaped portions and serving to contain an electric battery and coil.

In the accompanying drawings, Figure 1 is a side view of a chandelier and a vertical section of a holder and appurtenances, including an electric battery and a coil; and Fig. 2 is a plan of the holder.

Similar letters of reference designate corresponding parts in both figures.

A designates the stem of a gas-fixture of ordinary construction, and B designates the arms thereof. These parts, as shown, are intended to be made of metal. At the ends of the arms are burners C, which are intended to be made of metal.

Each burner has a stationary contact-piece or electrode, D, and a movable contact-piece or electrode, E, which is adapted to swing past the stationary contact-piece and produce an electric spark for lighting gas issuing from the burner-tip. The movable contact-pieces or electrodes are insulated from the stationary contact-pieces or electrodes. I do not here claim these contact-pieces or electrodes or the appurtenances thereof, as I have made them the subject of another application for Letters Patent.

F designates a holder consisting, as here shown, of two rings or sockets, a a', having shanks b b', provided with clamping-pieces c c', which fit the stem of the chandelier, and are

clamped to the same, so as to be fastened thereto by screws d d', passing loosely through one of the clamping-pieces and working in tapped holes in the other. All these parts may be 55 made of metal.

It is advantageous to make the clamping-pieces separable, because they may then be applied to a chandelier without removing it from its support, as would be necessary to 60 enable a single clamping-piece to be slipped over the top of the stem of the chandelier. A single clamping-piece and set-screw may, however, be employed when this objection will not be a serious one.

65 The holder may be secured in any desirable position upon the stem of the chandelier. Preferably, it will be arranged near the top.

G designates a case preferably made of sheet metal, which is inserted in the ring a, 70 and has a circumferential shoulder, e, which rests upon the top of the ring. This case may be made of any ornamental configuration which will admit of its being inserted in the ring a. It contains an electric battery, 75 H, which may be of any approved style, and preferably has an ornamental removable cover, G'.

I designates a case, which, preferably, will be made like the case G, and provided with a 80 shoulder, f, to rest upon the ring a', and a removable ornamental cover, I'. This case contains a coil, K, of insulated wire.

A wire, J, leads from a binding-post, g, which is in electrical communication with one pole 85 of the battery, through an opening in the case G or its cover G'. It is shown as connected to a piece of metal, L, which is clamped between the clamp of the holder and the stem of the chandelier. It is thus in electrical 90 communication with the chandelier, the burners thereof, and their stationary contact pieces or electrodes D.

A wire, J', extends from a binding-post, g', which is in electrical communication with the 95 other pole of the battery to a binding-post, h, which is in electrical communication with one end of the coil K.

A wire, J², extends from a binding-post, h', which is in electrical communication with the 100 other end of the coil K to wires J³, extending to the movable contact-pieces or electrodes E.

It will be seen that by my improvement I provide for applying electric lighting appliances to a gas-fixture at a slight expense and without occasioning any difficulty in wiring 5 for circuits or marring the appearance of the fixture.

What I claim as my invention, and desire to secure by Letters Patent, is—

A clamp or attachment made in two sections 10 connected, so as to admit of their separation to enable them to be slipped onto the stem

of a gas-fixture transversely to the length of the latter, and so as to admit of their being clamped upon the same, said clamp having ring-shaped portions, and being combined 15 with cases fitted in the ring-shaped portions, and serving to contain an electric battery and coil, substantially as specified.

C. A. HUSSEY.
